UNITED STATES PATENT OFFICE.

HERMANN LEMP, OF LYNN, MASSACHUSETTS, ASSIGNOR TO GENERAL ELECTRIC COMPANY, A CORPORATION OF NEW YORK.

FUEL-SUPPLY SYSTEM FOR EXPLOSIVE-ENGINES.

1,025,814.

Specification of Letters Patent.

Patented May 7, 1912.

Application filed May 23, 1906. Serial No. 318,338.

To all whom it may concern:

Be it known that I, HERMANN LEMP, a citizen of the United States, residing at Lynn, county of Essex, State of Massachusetts, have invented certain new and useful improvements in Fuel-Supply Systems for Explosive-Engines, of which the following is a specification.

The present invention relates to fuel supply systems for explosive engines, especially those used on automobiles, launches, etc.

Automobile engines are commonly supplied with gasoline by means of a float feed carbureter comprising a chamber containing a float that is attached to a valve, the latter regulating the admission of gasoline to the chamber and to the engine. Connected with the chamber, and between it and the engine, is a nozzle for supplying the necessary amount of gasoline to the air, as the latter flows past it to form an explosive mixture of the proper character. The float feed mechanism of this type of carbureter has always been a delicate piece of apparatus and uncertain in its operation, and therefore a source of trouble, largely because the variations in pressure due to the suction of the piston of the engine are slight. Moreover, the carbureter either has to be supplied by gravity from a tank, which is sometimes difficult to arrange in an automobile, by air-pressure, requiring attention on the part of the operator when the tank is situated below the carbureter, or by the exhaust of the engine.

The object of the invention is to overcome the disadvantages set forth above by dispensing with the float fed mechanism and its uncertainty of operation, and to substitute therefor a suitable chamber for feeding the spraying nozzle which is constantly supplied with gasoline in excess of the requirements, the said chamber being provided with an outlet at a given elevation so that the excess gasoline at any given time is carried off, as for example, by being returned to the supply tank.

A further object of the invention is to provide, in addition to the foregoing, a means for positively forcing gasoline from the supply tank into the chamber so that the tank can be placed wherever it is the most convenient and accessible, either above or below the said chamber.

In carrying out my invention, a vessel is provided containing a chamber of suitable size that is connected to the spraying nozzle, and also to the source of supply. Communicating with the chamber in the vessel, is an outlet or overflow through which the excess gasoline is returned to the supply tank. The outlet or overflow is preferably adjustable as to elevation, and is commonly set slightly below the discharge end of the spraying or discharge nozzle. Gasoline is conveyed from the supply tank to the vessel by a pump which is so constructed and arranged that it is adapted to operate by the variations of pressure in the explosion or working cylinder of the engine, as for example, the explosion pressure causing the discharge stroke of the pump, and the suction pressure the suction stroke. This arrangement obviates the use of working members connecting the piston of the pump with the crank shafts or other part moving with or driven by the engine. Furthermore, the pump can be located at any convenient point. By preference, I locate it below the level of the fuel tank so that its valves are normally flooded. The pump is of the diaphragm type and is of sufficient capacity to supply on each stroke an amount exceeding the maximum demand of the carbureter, the surplus being returned or by-passed to the tank. This insures an abundant supply for the maximum demand at all times and by means of the free by-pass the possibility of flooding the carbureter is prevented. The pump can be so designed as to output, that a substantially continuous flow can be maintained so that a single pump will be sufficient for an engine of any number of cylinders.

The invention is also applicable to stationary gas engine plants, since by means of the pump the source of fuel supply can be isolated from the building to comply with insurance regulations and laws.

For a more detailed understanding of the organization and mode of operation of the invention, as well as the features of novelty, reference is to be had to the accompanying description and claims appended hereto.

In the accompanying drawing, which illustrates one embodiment of which the invention is capable, Figure 1 shows a fuel

supply system applied to a gas engine, the latter being only partially shown; Fig. 2 is a section of the pump taken on the line 2 2, Fig. 1; and Fig. 3 is a detail sectional view 5 of the pump.

Referring to the drawing, 1 represents a portion of an explosive engine, to the cylinder or cylinders of which the fuel charges are supplied through the inlet conduits 2.

- 10 These conduits connect with an air suction conduit 3 in which is located the carbureter 4. The open end of the conduit 3 is not shown but the air enters in the usual manner through a suitable screened opening and 15 flows in the direction indicated by the arrows. The carbureter comprises a mixing chamber 5 containing a spray nozzle 6, through which chamber the air passes. The nozzle communicates with a fuel-containing 20 chamber 7 and receives fuel therefrom. The quantity of fuel discharged by the nozzle is controlled in the usual manner by a needle valve shown at 8 and the amount of air or 25 mixture may be controlled by a throttle valve 9, the details of which are not essential to an understanding of the present invention.

Suitably located with respect to the carbureter, preferably below the same so that 30 any surplus fuel may be returned thereto by gravity, is a fuel tank 10 which connects with the fuel chamber 7 of the carbureter through the supply pipe 11. In the supply pipe is a pump 12 by which the fuel is fed 35 positively to the carbureter. Referring to Fig. 2 the pump comprises a casing 13 formed of two disks bolted together and shaped to form a shallow chamber. In the chamber, and dividing it into two compartments, is arranged a diaphragm 14 secured 40 at its edge between the disks. One compartment communicates through the passages 15 and 16, Figs. 2 and 3, with the supply pipe 11, and as the diaphragm moves back and forth, fuel is drawn into the compartment and then discharged therefrom. At the ends of the passage 16 are formed 45 valve chambers in which are located, respectively, a suction valve 17 and a delivery valve 18, Fig. 3. The compartment on the opposite side of the diaphragm communicates with the compression space or combustion chamber of the engine cylinder through the conduit 19. By virtue of this, when 50 the pressure in the engine cylinder reaches a certain point, as for instance at the time of explosion, the fluid pressure acts through the conduit upon the diaphragm and moves it to the right, Fig. 2. This forces out the 55 charge of fuel previously drawn in the compartment on the right side of the diaphragm. When the pressure on the engine cylinder falls sufficiently, as during the suction stroke or during the period of exhaust, 60 the diaphragm returns or moves to the left.

and draws in a charge of fuel. This suction stroke may be due entirely to the fall in pressure in the engine cylinder or it may be caused by a spring or by a normal bias imparted to the diaphragm. Interposed in 70 the conduit 19, and between the diaphragm and the engine cylinder, is a small body of viscous substance, such as glycerin, which serves to prevent the hot gases affecting the diaphragm.

In the fuel-containing chamber of the carbureter is an overflow pipe 20 around which is threaded a sleeve 21 forming a dam that can be adjusted to vary the height of the fuel for obtaining the proper level at 80 the spraying nozzle. The over-flow pipe is connected to the tank 10 by means of the conduit 22. The upper end of the pipe 20 is surrounded by a cylindrical wall 20^a to reduce the effect of splashing in the chamber. The pump is so designed as to give an output exceeding the amount that is discharged at the spraying nozzle during each suction stroke of the engine and the excess amount over-flows and returns to the tank. 90 It will thus be seen that any change in the level of the parts of the vehicle will not affect the amount of fuel discharged from the spraying nozzle, and furthermore, there is always sufficient fuel present in the fuel-containing chamber 7 to meet the maximum demand. In order to equalize the pressure within the fuel-containing chamber and to admit air a screened vent 23 is provided.

To fill the carbureter and the tank a filling pipe 24 having a shut-off valve 25 is employed, which for simplicity connects with the supply pipe 11 adjacent the carbureter. In some systems a reserve tank or reservoir may be provided, preferably located above the level of the carbureter, and the pipe 24 is connected therewith to receive the fuel under gravity. If no such reserve tank is employed the fuel is supplied to the filling pipe in the usual manner. In the filling process the needle valve 8 of the carbureter is first closed and then the valve 25 opened. Fuel thereupon flows into the chamber 7 of the carbureter and after filling the same to its normal height over-flows and 100 fills the tank 10. To indicate when the tank is full an overflow or stand-pipe 26 is used which also serves as a vent to admit air as the pump draws off the fuel. The opening of this pipe is preferably fitted with a 105 screen to protect the tank in case of accident from flames. After the carbureter and tank are filled, the valve 25 is closed and the needle valve 8 opened to supply the charge 110 as soon as the engine is started. Immediately upon starting the engine the pump is operated, since the diaphragm chamber 115 thereof is in permanent communication with the interior of the engine cylinder.

In accordance with the provisions of the 120

patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new, and desire to secure by Letters Patent of the United States, is,—

1. The combination with an explosive engine, a carbureter therefor comprising a mixing chamber, a fuel containing chamber, a spraying nozzle in the first chamber to 15 which fuel flows by gravity from the second chamber, and an overflow pipe in the second chamber which determines the level of the fuel in said chamber with respect to the height of the spraying nozzle, of a fuel tank, 20 a connection between the overflow pipe and the tank which constitutes a by-pass, and a diaphragm pump between the carbureter and the tank which is operated by pressure transmitted from the combustion chamber of 25 the engine, said pump being located adjacent to the tank and below the level thereof

so that fuel will flow by gravity to the pump and keep it flooded with fuel.

2. The combination with a carbureter comprising a mixing chamber, a fuel containing chamber, a spraying nozzle in the mixing chamber to which the fuel flows by gravity from the second chamber; and an overflow pipe in the second chamber, which determines the level of the fuel in said 30 chamber with respect to the height of the spraying nozzle, of a fuel tank, a connection between the overflow pipe and the tank which constitutes a by-pass, a diaphragm pump between the carbureter and the tank 40 which is operated by fluid pressure and to which the fuel flows by gravity from the tank, and a filling device so located and arranged as to first fill the fuel-containing 45 chamber of the carbureter and thereafter fill the tank through the by-pass.

In witness whereof, I have hereunto set my hand this fifteenth day of May, 1906.

HERMANN LEMP.
